COUPLER

Edmund P. Kinne and Frank H. Kayler, **Alliance, Ohio, assignors to American Steel Foundries, Chicago, Ill., a corporation of New Jersey**

Application October 18, 1943, Serial No. 506,644

20 Claims. (Cl. 213—104)

Our invention relates to car couplers and particularly to an automatic type of tight lock coupler especially suitable for use on mine or industrial cars.

Our invention is an improvement of the car coupler more particularly described in United States Patent No. 2,271,770, issued February 3, 1942, in the name Edmund P. Kinne, and United States Patent No. 2,271,839, issued February 3, 1942, in the name Frank H. Kayler.

The lockset arrangement for this type of coupler as commonly used and as described in the above-mentioned Kayler patent, No. 2,271,839, provides that each time the couplers separate after being lockset, the lockset will be released thereby and the lock returned to normal position for locking upon the next engagement of the coupler with a mating coupler. This arrangement insures that coupling will always take place when mating couplers meet without the requirement of any manual operation to put the parts in position for coupling.

Under certain conditions prevailing in mines and sometimes in other operations, as when a car is spotted on a dump or on a hoist, it is sometimes required that a mating car be uncoupled and separated from an adjacent car in order to permit dumping of one car. When the cars are engaged again after dumping, as, for example, to push one car off of the dump or hoist, the couplers must not be permitted to lock but the pushed car must be free to run under the impulse imparted to it while the pushing car remains on the hoist or dump.

In order to permit this type of operation, an auxiliary lockset is required over and above that above mentioned, which will permit couplers to engage each other without coupling. By the use of such an auxiliary lockset, the coupler parts may thus be kept in unlocked position until the unlocking arm or lever is released from the auxiliary lockset either by manual means or automatically by tripping devices such as may be mounted for that purpose on the track in proper position between the rails. Such a tripper may consist of a cam or lever pivotally and resiliently mounted in such manner as to cause the auxiliary anticerp to be released by engagement of the trip lever with the operating arm of the coupler. The resilient means holding said trip lever in position may be effective to trip the auxiliary lockset while at the same time readily movable out of position by a car body which may pass thereover.

The general object of our invention, therefore, is to devise a novel and practicable form of aux-

iliary lockset for such a coupler as that above mentioned.

Our novel coupler contemplates a coupler such as that described, having a normal lockset and lock-to-the-lock which functions by engagement with a portion of a mating coupler as well as an auxiliary lockset which may function by engagement with a portion of the lockset coupler.

Our invention also contemplates a novel form of one-piece unlocking or operating arm having at one end lock connecting means, at the opposite end link connecting means, and at intermediate points a normal lockset shoulder and an auxiliary lockset shoulder; and further, such an operating arm wherein said normal lockset shoulder may be at the top of said arm and the auxiliary lockset shoulder may be at one side thereof.

In the drawing, Figure 1 is a top plan view, partly in section, of mating couplers embodying our invention.

Figure 1A is a fragmentary view in side elevation of the locked couplers as shown in Figure 1, the section being taken substantially in the vertical plane indicated by the line A—A of Figure 1 and looking upward.

Figure 2 is a sectional view through the mating couplers approximately in the vertical transverse plane indicated by the line 2—2 of Figure 1.

Figures 3, 4 and 5 show the detail of our novel form of operating arm, Figure 3 being a top plan view thereof, Figure 4 a side elevation taken from the bottom as seen in Figure 3, and Figure 5 an end view taken from the left as seen in Figure 4.

As illustrated, the couplers 2 and 4 are identical, each having a nose portion 6 housing a lock 8, pivoted at 10 within said nose and arranged for abutment as at 12 with the lock of the mating coupler, all as described in the before-mentioned Kayler patent. Each lock 8 is engaged by an operating arm 14, the hook end 16 (Figure 4) of said operating arm engaging over the bridge 18 of the lock 8 and the opposite end of the operating arm being recessed as at 20 for the reception of the link 22 which may be pivotally secured thereto as at 24, said link forming a portion of an operating chain.

When the lock parts are in normal locked position, as illustrated in coupler 4 (Figure 1), the operating arm 14 is withdrawn into the coupler head and the associated compression spring 26 is in its most expanded position under compression between the spring seat 28 at the hook end of the operating rod (Figures 3 and 4) and the side wall 30 of the coupler nose. As also illustrated in Figure 1, the locking parts of the coupler 2 are in

auxiliary lockset position wherein the operating arm 14 is withdrawn sufficiently to permit the auxiliary lockset shoulder 32 to engage as at 34 the tapered flange 36 on the side of the coupler head. When the parts of the mating couplers are in these respective positions, the couplers obviously may be parted, since the opposing locks 8, 8 may pass each other as at 38 without engaging.

Looking at Figure 2 which illustrates the nose of the coupler 2 received within the head cavity of the coupler 4, it may be seen that the normal lockset shoulder 40 on the operating arm 14 of said coupler 2 is substantially below and clear of the normal lockset notch 42 on the side wall of the coupler 4, said normal lockset arrangement being designed to function as more particularly described in said Kayler Patent No. 2,271,839.

It will be understood that pulling of the chain 22, which is connected to the operating arm 14, normally results in the elevation of the arm 14 sufficiently so that the normal lockset shoulder 40 will engage the lockset notch 42 of the mating coupler. However, when it is desired, the auxiliary lockset may be caused to function by manual operation of the arm 14 in a lateral direction to engage the flange 36, as already described and illustrated in Figure 1.

The detail of our novel form of operating arm is shown in Figures 3, 4 and 5. It will be noted that the auxiliary lockset shoulder 32 is formed on the side of the operating arm, whereas the normal lockset shoulder 40 is formed on top of the arm. Looking at Figure 2, it will be observed that the flange 36 is extended above the lockset portion as at 43, said top portion 43 of the flange 36 being relatively wide as compared with the portion 34. The portion 43 thereby acts as a guard so that the auxiliary lockset shoulder 34 may not be engaged when the operating arm 14 is in the elevated position for engagement of the normal lockset shoulder 40 against the lockset notch 42 of the mating coupler.

In manual operation of the auxiliary lockset, movement of the operating arm 14 is in the direction of its length and laterally for engagement as indicated in Figure 1. This auxiliary lockset at 32, 34, being on the side wall of the lockset coupler, is independent of the mating coupler and will not be affected when the couplers are parted. On the other hand, in the normal lockset at 40, 42, the operating arm of the lockset coupler is engaged with the side wall of the mating coupler and parting of the couplers releases the lockset to provide for automatic locking upon re-engagement with the same or another coupler.

It will be understood that the upper portion 43 of the vertical flange 36 affords a guard along which the auxiliary lockset shoulder 32 may ride as the operating arm is moved into engagement with the normal lockset shoulder 42 of a mating coupler. Thus, when the operating arm 14 is moved in an upward direction, any possible engagement of the auxiliary lockset shoulder at 34 is prevented because the spring 26 will go solid before the auxiliary lockset shoulder 32 can clear the edge of the widened portion 43. In other words, the solid height of the spring 26 measures the amount that the operating arm can be withdrawn and this is such a distance that the auxiliary lockset shoulder 32 will not clear the edge of the widened portion 43 on the flange 36.

It will thus be seen that in our novel arrangement a normal lockset is provided for the operating arm of a lockset coupler on a portion of a mating coupler while an auxiliary lockset may

also be provided for the operating arm of said lockset coupler on a portion of the head thereof. Thus, when the auxiliary lockset is in engagement, it is independent of the mating coupler and separation of the couplers does not disturb the unlocking arm from its engagement in lockset position; on the other hand, when the normal lockset is in engagement, parting of the couplers releases it as already described.

10 By this means either of the two lockset arrangements may be selectively used, one of which is automatically released upon separation from a mating coupler to provide for automatic locking upon re-engagement with the same or another coupler; 15 the other will be unaffected by separation from or re-engagement with a mating coupler and must be released by manual means or by special tripping means. When the auxiliary lockset is in position, therefore, a coupler may be engaged with a mating coupler for the purpose of pushing the car upon which the mating coupler is mounted without actually causing coupling therewith. As already described, the track over which the cars are operated may be provided with a tripping arm which may be effective to strike and release the auxiliary lockset when the car has passed away from the hoist or dump, as the case may be.

It is to be understood that we do not wish to be limited by the exact embodiment of the device shown which is merely by way of illustration and not limitation as various and other forms of the device will, of course, be apparent to those skilled in the art without departing from the spirit 35 of the invention or the scope of the claims.

We claim:

1. In an automatic car coupling, mating coupler heads each having locks arranged to pivot in a horizontal plane and adapted to engage each other, an unlocking arm for each lock having a portion projecting through the side wall of the supporting coupler head, and a compression spring associated with each arm, and operable to move said arm and the associated lock to locking position upon release of said arm from lockset each of said arms having angularly spaced lockset shoulders adapted selectively to engage means on said respective heads, positioning of either of said arms on certain of said lockset shoulders being effective to maintain said lockset upon parting of said coupling, and positioning of said arm upon the other of said lockset shoulders causing said lockset to be released upon parting of said coupling.

2. In an automatic tight lock coupling, mating coupler heads each having locking means comprising a pivoted lock and operating means therefor including a lock actuating arm normally housed within the associated coupler head, spring means associated with each arm for returning the associated lock to locking position upon release of said arm from lockset, each arm having a normal lockset for engagement with the mating coupler head and an alternate lockset for engagement with the head carrying said arm, normal lockset position of either of said locks being such that parting of said couplers will release said normal lockset and alternate lockset of either of said locks being such that parting of said couplers may be effected without disturbing said alternate lockset.

3. In an automatic car coupling, mating coupler heads each having locks arranged to pivot in a horizontal plane and adapted to engage each other, an unlocking arm for each lock having a

portion projecting through the side wall of the supporting coupler head, and a compression spring associated with each arm for returning said arm to locking position when released from lockset, each of said arms having angularly spaced lockset shoulders selectively adapted to engage means on said respective heads, positioning of either of said arms on certain of said lockset shoulders being effective to maintain said lockset upon parting of said coupling and positioning of said arm upon the other of said lockset shoulders causing said lockset to be released upon parting of said coupling.

4. In an automatic car coupling, mating coupler heads each having locks arranged to pivot in a horizontal plane and adapted to engage each other, an unlocking arm for each lock having a portion projecting through the side wall of the supporting coupler head, and a compression spring associated with each arm for resisting movement of said arm from locking position, each of said arms having angularly spaced lockset shoulders adapted selectively to engage means on said respective heads, positioning of either of said arms on certain of said lockset shoulders being effective to withdraw the associated lock out of position for engagement with the lock of the mating head upon parting of said coupling.

5. In an automatic coupler, a coupler head, a lock pivoted therein for movement in a horizontal plane, an unlocking arm pivotally connected to said lock and resilient means under compression between a portion of said arm and the adjacent side wall of said head for resisting movement of said arm from locking position, said arm projecting through said head for connection to actuating means, and a plurality of lockset shoulders angularly spaced along said arm, one of said lockset shoulders being adapted to engage a ledge on said side wall and the other of said shoulders being adapted alternately to engage means on a mating coupler.

6. In an automatic tight lock coupling, mating coupler heads each having locking means comprising a pivoted lock and operating means therefor including a resiliently restrained lock actuating arm normally housed within the associated coupler head, each arm having a normal lockset for engagement with the mating coupler head and an alternate lockset for engagement with the head mounting said arm, normal lockset position of either of said locks being such that parting of said couplers will release said normal lockset.

7. In an automatic tight lock coupling, mating coupler heads each having locking means comprising a pivoted lock and operating means therefor including a resiliently restrained lock actuating arm normally housed within the associated coupler head, each of said arms having a normal lockset for engagement with the mating coupler head and an alternate lockset for engagement with the associated head, said normal lockset and alternate lockset being spaced along said arm at intermediate points thereof with said normal lockset shoulder on the top of said arm and said alternate lockset shoulder at one side thereof.

8. In an automatic tight lock coupling, mating coupler heads each having locking means comprising a pivoted lock and operating means therefor including a spring-resisted lock actuating arm normally housed within the associated coupler head, each of said arms having a normal lockset for engagement with the mating coupler head and an alternate lockset for engagement with the associated head, said normal lockset and alternate

lockset being angularly spaced along said arm at intermediate points thereof.

9. In an automatic tight lock coupling, mating coupler heads each presenting a pivoted lock with resilient means for urging said lock into engagement with the lock of the mating coupler, and operating means for each lock comprising an unlocking arm having a normal lockset shoulder for engagement with the head and an auxiliary lockset shoulder for alternate engagement with the coupler head on which said arm is mounted.

10. In an automatic tight lock coupling, mating coupler heads each having locking means comprising a pivoted lock and operating means therefor including a resiliently restrained lock actuating arm normally housed within the associated coupler head, each of said arms having a normal lockset for engagement with the mating coupler head and an alternate lockset for engagement with the head mounting said arm.

11. In an automatic coupler, a coupler head, a lock pivoted therein for movement in a horizontal plane, an unlocking arm pivotally connected to said lock and resilient means under compression between a portion of said arm and the adjacent side wall of said head for resisting unlocking movement of said arm, said arm projecting through said head for connection to actuating means, and a plurality of lockset shoulders angularly spaced along said arm for selective engagement with said head or alternately with a mating coupler head.

12. In an automatic car coupling, mating coupler heads each having locks arranged to pivot in a horizontal plane and adapted to engage each other, an unlocking arm for each lock having a portion projecting through the side wall of the supporting coupler head, and a compression spring associated with each arm for resisting unlocking movement thereof, each of said arms having angularly spaced lockset shoulders selectively adapted to engage means on said respective heads.

13. In an operating arm for an automatic coupler, lock connecting means at one end, means at the other end for connection to operating mechanism, and linearly spaced lockset shoulders at intermediate points on said arm, one of said lockset shoulders being angularly spaced about the longitudinal axis of said arm approximately ninety degrees from the other thereof.

14. An unlocking arm for an automatic coupler comprising lock connecting means at one end, means at the other end for connection to actuating mechanism, an auxiliary lockset shoulder spaced from said lock connecting means, and a normal lockset shoulder more remotely spaced therefrom and angularly positioned with respect to said first mentioned shoulder.

15. An unlocking arm for an automatic coupler comprising lock connecting means at one end, means at the other end for connection to actuating mechanism, a normal lockset shoulder linearly spaced from said lock connecting means, and an auxiliary lockset shoulder intermediate said normal shoulder and said lock connecting means and angularly positioned with respect thereto.

16. In an automatic tight lock coupling, mating coupler heads each presenting a resiliently restrained pivoted lock for engagement with the lock of the mating coupler, and operating means for each lock comprising an unlocking arm having lockset shoulders for selective engagement with means on said heads.

17. In an automatic coupling, a coupler head,

a mating coupler head, a resiliently restrained pivoted lock in each of said heads, and operating means for each of said locks including an actuating arm having angularly and linearly spaced lockset shoulders for selective engagement with lockset means on said respective heads. 5

18. In an operating arm for an automatic coupler, lock connecting means at one end, means at the other end for connection to operating mechanism, and angularly related lockset shoulders at 10 intermediate points on said arm.

19. An automatic car coupler having a head, a

resiliently restrained lock pivoted therein, and operating means for said lock including an operating arm having angularly spaced lockset shoulders adapted alternatively to engage means on said head and means on a mating head.

20. In an automatic car coupler, a head, a lock pivoted therein, and a resiliently reacting lock actuating arm having angularly spaced lockset means for selective engagement with means on said head and means on a mating head.
